(57) **CLAIM**

The ornamental design for a sports training mat, as shown and described.

DESCRIPTION

FIG. 1 is a top, isometric view of a sports training mat according to a first embodiment;

FIG. 2 is a top view thereof;

FIG. 3 is a bottom view thereof;

FIG. 4 is a left side view thereof;

FIG. 5 is a right side elevation view thereof;

FIG. 6 is a front view thereof;

FIG. 7 is a rear view thereof;

FIG. 8 is a top, isometric view of a sports training mat according to a second embodiment;

FIG. 9 is a top view thereof;

FIG. 10 is a bottom view thereof;

FIG. 11 is a left side view thereof;

FIG. 12 is a right side elevation view thereof;

FIG. 13 is a front view thereof; and,

FIG. 14 is a rear view thereof.

1 Claim, 10 Drawing Sheets
